UNITED STATES PATENT OFFICE.

FRANK C. DORMENT, OF KALAMAZOO, MICHIGAN, ASSIGNOR OF ONE-THIRD
TO HOWARD G. COLMAN, OF SAME PLACE.

ATOMIZER.

SPECIFICATION forming part of Letters Patent No. 642,211, dated January 30, 1900.

Application filed March 25, 1899. Serial No. 710,403. (No model.)

To all whom it may concern:

Be it known that I, FRANK C. DORMENT, of Kalamazoo, in the county of Kalamazoo and State of Michigan, have invented a new and 5 useful Improvement in a Combination Vapo-
rizer and Atomizer, of which the following is a full, clear, and exact description.

This invention relates to instruments for atomizing liquids—that is, discharging the 10 liquids by air-pressure in a more or less broken-up condition, like fine sprinkling or spray; and it also relates to instruments for vaporizing liquids—that is, converting the liquids into light cloud-like vapor and discharging 15 the same in a condition which floats in the air like smoke.

The objects of my invention are as follows: First, to produce a single instrument which 20 can be used for atomizing and vaporizing liquids at one and the same time and by the same operation; second, to produce a single instrument with improved features that can be used to either atomize or vaporize liquids, and thus obviate the expense and inconvenience 25 of purchasing and using a separate instrument for each separate use, and, third, improved features as the outgrowth of the peculiar construction and arrangement, as will appear in the detailed description and claims. 30 Reference is to be had to the accompanying drawings, forming a part of this specification, in which similar numerals of reference indicate corresponding parts in all the figures.

Figure 1 is a view showing the combined 35 device complete. Fig. 2 is a sectional view of Fig. 1 on line *a a*. Fig. 3 is a detail view of the atomizing-tube 7. Fig. 4 is a detail view of the mouth or throat piece. Fig. 5 is a detail view of the nasal piece 9.

Referring to Figs. 1 and 2, the stopper 3 is 40 provided with an air-passage 4, assuming a right-angle course extending from the side and terminating through the lower surface of said stopper, the opening in the other side thereof being screw-threaded and adapted to receive the threaded end of the air-receiving tube 14, while the opening in the lower surface is also screw-threaded and adapted to receive the nebulizing-tube 5. The round

opening 12, extending vertically through the 50 stopper 3, is screw-threaded at the upper surface thereof and adapted to receive the threaded end of the throat-tube 8. The lower end of the nasal piece 9 is adapted to be attached to the tapered end of the throat-tube 55 8 by fitting snugly over it. The long stem of the atomizing-tube 7, terminating at the upper end in a cap of larger diameter and having a portion of its surface threaded under the shoulder extension thereof, as shown in 60 Fig. 3, is adapted to be inserted in the hollow of the nasal piece 9 and throat-tube 8 and secured thereto by the threaded portion thereon engaging in the corresponding threaded portion in the opening in said nasal piece 65 9, substantially as shown in section in Fig. 2. At the bottom of the stopper 3 is a shoulder extension, as shown in Fig. 2, corresponding in diameter to that across the mouth of the bottle 1, the exterior portion of the neck 70 thereof being screw-threaded.

A cap 2 has an opening in the top thereof through which the upper portion of the stopper 3 is inserted, and the shoulder thereon abuts against the rim of said cap, as shown in 75 Fig. 2.

The stopper 3, with its attachments, is 80 adapted to be clamped to the mouth of the bottle 1 by tightening the screw-cap 2, which engages the threads on the neck of said bottle, as shown in Figs. 1 and 2, the washer 11 being employed between the contacting or abutting portion at the mouth of said bottle and stopper to make the fitting air-tight.

When it is desired to vaporize the liquid in 85 the receptacle 1, the atomizing-tube may be removed, and when pressure is applied to the air-bulb 13, which is connected with the air-receiving tube 14, air is forced through the nebulizing-tube 5, and the adjustable 90 suction-tube in the lower end thereof being adjusted so that the upper extending end is nearly in line with the center of the horizontal portion of said tube 5 the current of air is 95 guided up over the top of the abrupt wall formed thereby and out through the opening 10 at the joint. This force of the air over the top of the tube 6 causes a suction and

draws the liquid up through said tube 6, where it unites with the air and is forced out through the outlet 10 in the form of spray against the walls of the receptacle, by means 5 of which said spray is vaporized and discharged through the vapor-eduction passage, whether it be through the throat-tube 8, with the nasal piece 9 and the vaporizing-tube 7 detached, or whether the vapor be discharged 10 without detaching these parts 7 and 9, in the manner explained farther on in connection with the combined use of the instrument at a single operation, in which use it will be seen 15 that the atomizing-tube 7 would not be detached.

It is seen that the construction of parts 5 10 and their arrangement with the inside of a portion of the wall of the bottle 1 constitutes the vaporizer proper and produces the 20 vapor or light cloud-like element from the liquids.

The small suction-tube 6 is adapted to telescope snugly in the vertical lower end of the nebulizing-tube 5 and is adjustable therein, 25 so as to increase or decrease the force of the air passing over the upper end thereof for the purpose of producing a heavy or light vapor, as may be desired.

By reference to Fig. 2, it will be seen that 30 the atomizing-tube 7 is smaller than the passage through the throat-tube 8 and through the nasal piece 9, which passage said tube 7 occupies, thus leaving a space between the atomizing-tube 7 and the inner surface of 35 the wall of said passage. This space also continues down through the stopper 3.

When it is desired to atomize a liquid which is in the receptacle 1, the nebulizing-tube 5 may be removed and the atomizing-tube 7 inserted, as before described, and shown in 40 Figs. 1 and 2, and when air is forced into said receptacle through the receiving-tube 14 the liquid is forced up through the small inlet-opening in the bottom of said tube 7, while a 45 portion of the air passes up through the space between tube 7 and the interior walls of tube 8 and nasal piece 9 and out through the openings 15, where the force of air cuts the minute liquid stream which is passing up within the 50 vaporizing-tube 7 at right angles and assists in breaking up said minute stream of liquid into an atomized condition, which is delivered or forced out of the upper end of said tube 7.

In treating the nasal passages to vapor 55 alone the tube 7 is detached and the nasal piece 9 is attached on the end of the throat-tube 8. When treating the mouth, throat, and lungs, the parts 7 and 9 may be removed, if desired, or either of them. When both are 60 removed, the vapor can be discharged in increased volume. Since the liquids in being converted into vapor come in contact with the inside of the wall of the bottle 1, any liquids unconverted into vapor which thus 65 come in contact run back into the volume of

liquid in the bottle. It is thus important that the vaporizing be done within the bottle where the liquids are.

All the parts of the instrument are made to be detachable from each other, as shown, 70 whereby they can be easily and thoroughly cleaned in addition to the other specified objects of such construction. The upper portion of the vapor-eduction passage, which is, as in Fig. 2, the nasal piece 9, is interiorly 75 chambered, forming a compressed-air chamber 17. This nasal piece 9 also forms a portion of the air-passage whenever used. In the use of the instrument this chamber soon becomes filled with air, for the air does not 80 pass out as fast as it comes in. When a proper air-pressure is established, there is uniformity in the pressure and in the effect on the patient and hence no annoyance to the patient in either the separate or combined uses of the instrument. 85

Having described the separate uses and referred to the combined use, I will now describe the latter. In treating patients it is frequently desirable and sometimes necessary to administer medicated liquids or oils in both an atomized and a vaporized condition and this at one and the same time and operation. It is very convenient to do so, besides being beneficial. To illustrate an instance: The passages of the nose often need a treatment of the liquids in their heavier or atomized form, while the deeper air-passages need a treatment of the lighter or vaporized form. My single instrument is especially 100 adapted for this combined use. The operation is as follows: When the instrument is arranged as in Figs. 1 and 2 ready for the combined use, place the upper end in the nose and operate the bulb 13. The atomized 105 liquids will pass out of said end into the nose and be deposited in its passages while the vapor which is made in the bottle passes out through the space between the atomizing-tube 7 and the inner wall of the tube 8 and the 110 nasal piece 9 and out through the holes 15 and on into the nose and on beyond into the deeper air-passages of the head, throat, and lungs. In this use of the instrument the atomized and 115 vaporized liquids are both discharged out of the same outlet in the end of the tube 7.

Having thus described my invention, what I claim as new, and desire to secure by Letters Patent, is—

The combination of a receptacle for holding 120 liquids, an air-receiving tube through which air is forced into the receptacle, a vapor-eduction tube comprising the throat-tube and nasal piece, the delivery end of which is internally screw-threaded, and near said end being 125 enlarged forming a compressed-air chamber, an atomizing-tube for detachable insertion in said vapor-eduction tube and of a size to leave a space between the atomizing-tube and the inner wall of the vapor-eduction tube, said 130

atomizing-tube being externally screw-threaded at the upper end to fit into the screw-threaded hole of the vapor-eduction tube, and provided with the right-angled holes leading into it from the compressed-air chamber, and a construction and arrangement in the liquid-receptacle for vaporizing liquids therein, substantially as set forth.

In testimony of the foregoing I have hereunto set my hand in the presence of two witnesses.

FRANK C. DORMENT.
